UNITED STATES PATENT OFFICE.

ALBERT F. FIFIELD, OF ELIZABETH, NEW JERSEY, AND WILLIAM L. BARRON, OF NEW YORK, N. Y., ASSIGNORS TO THE SINGER MANUFACTURING COMPANY, A CORPORATION OF NEW JERSEY.

BUTTON-SEWING MACHINE.

1,243,927.

Specification of Letters Patent. Patented Oct. 23, 1917.

Application filed September 24, 1915. Serial No. 52,339.

To all whom it may concern:

Be it known that we, ALBERT F. FIFIELD and WILLIAM L. BARRON, citizens of the United States, residing, respectively, at

- 5 Elizabeth, in the county of Union and State of New Jersey, and New York, in the county of New York and State of New York, have invented certain new and useful Improvements in Button-Sewing Machines, of which
10 the following is a specification, reference being had therein to the accompanying drawings.

This invention relates to improvements in button sewing machines and particularly
15 that class of machines adapted to act upon integral shank buttons, and it has for its object to provide button-holding means adapted to accommodate different sizes and varieties of such types of buttons, and means
20 for relatively moving the button-holding and the work-supporting elements of the machine to permit easy insertion and withdrawal of the work.

The improvements are adapted for embodiment in a button-sewing machine of the Singer type, as disclosed in United States patent to Sullivan, No. 777,564, of December 13, 1904, in which the jogging work-clamp comprises a lower plate formed with
25 a needle aperture and an upper plate supported upon the lower plate and spring-pressed toward the latter.

In the present embodiment of the invention, the upper work-clamp plate is formed
35 with a channel-way to receive and guide an adjustable carrier for two button-holding arms which at their ends are provided with seats to engage the head of a "self shank" button, the upper button-holding arm being
40 pivotally mounted upon the carrier and spring-pressed to yieldingly engage the button-head, the said arm also being provided with a lifting lever by means of which it may be elevated to release the button. Fulfilled upon the lower work-clamp plate is a rock-arm which carries the usual work-supporting block, and the said rock-arm is connected by means of a bellcrank-lever and link with a lifting lever for the work-clamp,
45 so that the work supporting block is swung laterally when the work-clamp is raised, to provide ample space between the button-holding arms and the block for easy withdrawal or insertion of the work.

50 In the drawings, Figure 1 is a perspective

view of a sewing machine embodying the improvements, and Fig. 2 is a sectional elevation of the button-holding arms and their immediate supporting members. Fig. 3 is a cross-section on line 3—3, Fig. 2, and Fig. 4 is a cross-section on line 4—4, Fig. 2. Fig. 5 is a detail view of the work-supporting block and its supporting rock-arm.

The improvements are shown embodied in a sewing machine formed with the base 65 A, standard B and overhanging arm C terminating in the head D, the usual vertical reciprocatory needle-bar 1 being mounted in the head D and carrying the needle 2. The head D also supports the clamp lifting-bar 70 3 carrying at its lower end the horizontally disposed pin 4 which is embraced by a member of the work-clamp, as hereinafter described. At its lower end, the bar 3 carries a guide-foot 5 apertured to receive and guide 75 the needle.

Resting upon the throat-plate 6 is a flat work-supporting plate 7 forming the lower member of the work-holder, and apertured, as usual, to permit passage of the needle. 80 The plate 7 is secured by means of the screwstud 8 upon the forward end of the slide-bar 9 which carries at its rearward end the block 10 recessed to receive the rearward end of the upper work-clamp arm 11, the latter 85 having an offset opposite-end portion 12 terminating in the supporting plate 12^x for the button-holder.

The button holder comprises a sliding carrier 13 formed with the reduced base-portion 13^x fitted to slide within a channel-way formed in the plate 12^x. Near its rear end the carrier is formed with a socket to receive the depending lug 14 of the upper button-holding arm 15, the said arm being 90 formed in two sections connected by means of the screws 16. The depending lug 14 of arm 15 is apertured to receive a pin 17 which enters alined apertures formed in the depending portion of the carrier and serves to pivotally connect the arm thereto. At its forward end the arm 15 is formed with the angular button - holding jaw 15^x. Secured upon the lower face of the carrier 13 by means of the screws 18 is the lower 100 button-holding arm 19 formed with the angular button-holding jaw 20 adapted to engage the lower edge of the button 6, the upper edge of which is engaged by the similar button jaw 15^x at the end of arm 15. 110

The carrier is provided with a vertically-extending lug 21 having a threaded aperture to receive an adjusting screw 22, the latter being held against endwise motion 5 by means of the slotted stop member 23 formed integrally with the plate 12^x and engaging the collars 22^x fixed upon the screw. By manipulating the adjusting screw 22, the button-holder may be moved endwise to 10 position the shank aperture of the button with respect to the needle.

The upper button-holding arm is pressed downwardly to hold the button under yielding pressure, by means of a spiral spring 15 24 surrounding a stud 25 secured to the carrier 13, the upper end of the spring being engaged by the lower face of a thumb-nut 27 which may be manipulated to regulate the spring-pressure. The limit of 20 action of the spring 24 is regulated by a stop screw 28 carried by the upper button-holding arm 15 and engaging the upper face of the carrier 13. For convenience in elevating the upper button-holding arm to 25 release a button and for the easy insertion of the succeeding button, the arm is provided, adjacent to its pivotal connection with the carrier, with a lever-arm 29 secured in position by means of the screw 16 and which 30 may be depressed to rock the arm upon its pivot-pin 17 against the pressure of the spring 24.

A work supporting-block 30 is provided at the rear of the button engaging jaws 35 15^x and 20. The said block is mounted on a stud 32 carried by a rock-arm 33 which is fulcrumed at 34 upon the slide-bar 9, a stud-screw 32^x serving to hold the block against displacement. By substituting a 40 suitable arm of a plurality of blocks 30 with which the machine is provided almost any sized shank bottom can be accommodated. The right-hand end of rock-arm 33 is bent upwardly and formed with a fork to embrace 45 a stud or pin 35 carried by the lower arm of a bellcrank-lever 36 fulcrumed at 37 upon a fixed bracket 38. The upper arm of bellcrank-lever 36 is apertured to receive a rod 39 connected at 40 with the work-clamp lifting lever 41, the latter being formed at one end with an aperture 41^x to receive a treadle-rod and at its opposite end with a fork 42 to embrace the clamp lifting bar 3 immediately below a collar 3^x fixed 55 thereon. Fitted upon the rod 39 immediately below the upper arm of the bellcrank-lever 36 is a buffer-spring 43, the lower end of which rests upon an adjustable collar 44, and a second adjustable collar 45 fitted upon the rod 39 above the bellcrank-lever arm serves to hold the latter in constant engagement with the buffer-spring.

The upper work-clamp arm 11 and the button-holding members supported thereon 60 may be elevated above the work held be-

tween the lower face of the button-holding jaw 20 and the work-supporting plate 7. For this purpose the supporting plate 12^x of the work-clamp arm has secured thereon a vertically disposed plate 46 formed with an 70 opening to receive the horizontally disposed pin 4 carried at the lower end of the clamp lifting bar 3, so that the said bar when elevated by means of the lifting lever 41 will move the arm 11 upwardly against the 75 pressure of spring 47. It will be seen also, that the lifting movement of lever 41 will, through elbow-lever 36 and rod 39, rock the bar 33 on its fulcrum to bodily move the work supporting-block 30 away from 80 the button-holding jaws to permit easy insertion or withdrawal of the work.

It is also to be noticed that the adjusting screw 22 affords means for moving or sliding the carrier 13 upon the supporting- 85 plate 12^x whereby the upper and lower jaws may be shifted horizontally in a direction at substantially right angles to the line of needle-actuation so that the aperture in the shank of the button may be properly located with respect to the needle.

Having thus set forth the nature of the invention, what we claim herein is:

1. The work-holding means comprising a work-supporting plate, a work-supporting block, a pair of spaced button-holding jaws overlying and spring-pressed toward the said plate, and means for simultaneously lifting the said jaws and retracting the work-supporting block. 95

2. The work-holding means comprising a work-supporting plate, a pair of spaced button-holding jaws overlying said plate, a carrier for the said jaws, a supporting member for the said carrier and means for adjusting the carrier upon its supporting member. 100

3. The work-holding means comprising a work-supporting plate, a pair of spaced button-holding jaws overlying the said plate, a work-supporting block mounted upon the said plate and means for moving the said block relatively to the button-holding jaws. 110

4. The work-holding means comprising a movable work-supporting plate, an arm connected for movement with the said work-supporting plate, a carrier adjustably mounted upon the said arm, two spaced and relatively movable arms mounted on the said carrier and provided with button-holding jaws, a spring acting upon one of the said relatively movable arms, and a lifting lever for moving the said relatively movable arm in opposition to its spring. 115

5. The work-holding means comprising a work-supporting plate, an arm connected for movement with the work-supporting plate, a carrier slidingly mounted upon the said arm, a second arm rigidly connected to 130

- the carrier and provided with a button-holding jaw, a third arm pivotally mounted upon the carrier and provided with a button-holding jaw, and means for moving the carrier relatively to its supporting arm.
6. The work-holding means comprising a movable work-supporting plate, an arm connected for movement with the work-supporting plate and formed with a channel-way, a carrier formed with a reduced depending portion slidingly fitted within said channel-way, an arm rigidly connected to the depending portion of the carrier and provided with a button-holding jaw, a second arm pivotally mounted upon the carrier and provided with a button-holding jaw, and means for moving the carrier relatively to its supporting arm.
- 10 7. The work-holding means comprising a work-supporting plate, a work-supporting block pivotally mounted upon the said plate, a pair of spaced button-holding jaws overlying the work-supporting plate, a lifting lever for the said jaws, and a connection between the said lever and the work-supporting block whereby the latter may be moved upon its pivot as the jaws are lifted.
- 15 8. The work-holding means comprising a work-supporting plate, an arm connected for movement with the work-supporting plate, a carrier slidingly supported upon the said arm, a second arm rigidly connected to the carrier and provided with a button-holding jaw, a third arm pivotally mounted upon the carrier and provided with a button-holding jaw, a spring acting upon the third arm, and a stop device to determine the limit of action of the spring.
- 20 9. In a button sewing machine having a stitch-forming mechanism including a needle, a work-holder including a pair of vertically separated button-holding jaws, means for adjusting said jaws relatively to accommodate different sized buttons, means
- 25 40 45
- the aperture in shank buttons may be properly located with respect to the needle.
10. In a machine for sewing on shank buttons having stitch-forming mechanism including a needle, a work-holder, including a pair of vertically spaced button-holding jaws, means for adjusting said jaws relatively in a substantially vertical plane to accommodate different sized buttons, means for adjusting said jaws bodily in a substantially horizontal plane to locate the aperture of different sized buttons properly with respect to the needle.
- 50 55 60 65 70
11. In a machine for sewing on shank buttons having stitch-forming mechanism including a needle, a work-holder, including a work-supporting plate, a pair of spaced button-holding jaws overlying said plate, the lower of said jaws being relatively fixed horizontally and the upper of said jaws being movable relatively thereto, means urging said upper jaw toward said lower jaw and means for simultaneously moving said jaws toward or from the needle without changing the relative position of the jaws.
- 75 80
12. In a machine for sewing on shank buttons having stitch-forming mechanism including a needle, a work-holder including a pair of vertically spaced button-holding jaws, a work-supporting block, and common means for shifting said button-holding jaws and supporting block to facilitate introduction of the work.
- 85 13. In a machine for sewing on shank buttons, having stitch-forming mechanism including a needle, a work-holder including a pair of button-holding jaws and a work-supporting block, a pivoted lever for supporting said block, and a connection between said block and said lever permitting removal and replacement of said block.
- In testimony whereof, we have signed our names to this specification.
- ALBERT F. FIFIELD.
WILLIAM L. BARRON.
